Primary Examiner — Catherine R Oliver-Garcia(57) **CLAIM**

The ornamental design for a utility athletic belt, as shown and described.

DESCRIPTION

FIG. 1 is a top right perspective view of a utility athletic belt; FIG. 2 is a bottom left perspective view thereof; FIG. 3 is a top plan view thereof; FIG. 4 is a bottom plan view thereof; FIG. 5 is a front elevational view thereof; FIG. 6 is a rear elevational view thereof; FIG. 7 is a right side elevational view thereof; and, FIG. 8 is a left side elevational view thereof.

The broken line showing of buckles is included for the purpose of illustrating environmental structure and forms no part of the claimed design.
